CASKET TRUCK

Harry T. Floyd, St. Louis, Mo.

Application September 27, 1934, Serial No. 745,752

1 Claim. (Cl. 280—36)

This invention relates to certain new and useful improvements in casket trucks the peculiarities of which will be hereinafter described and claimed.

5 The main objects of my invention are first, to improve the appearance and operation of casket trucks using lazy-tong connections between the corner posts; second, to hide within the posts the sliding members to which the upper ends of the 10 lazy-tong bars are pivoted; third, to lock said members in any adjusted position; fourth, to lock the caster wheels in closed position; and other objects hereinafter described and claimed.

In the accompanying drawings in which like 15 reference numerals indicate corresponding parts,

Fig. 1 represents a plan view of a casket truck opened to largest operative position and exemplifying my improvements;

Fig. 2, a side elevation of the same;

20 Fig. 2A, a detail showing the locking position of the center handle block;

Fig. 3, a side view of the truck in its closed position;

25 Fig. 4, an enlarged detail of the upper part of a corner post, viewed diagonally from inside the truck frame;

Fig. 5, a vertical section on the line 5—5 of Fig. 4;

30 Fig. 6, a horizontal plan view and section of a corner post on the line 6—6 of Fig. 2; and

Fig. 7, a vertical section on the line 7—7 of Fig. 6.

Referring to the drawings the numeral 8 designates the corner posts connected by lazy-tongs or 35 other extendible bars forming sides 9 and ends 10 of a rectangular frame, which is adjustable horizontally to various sizes by operating said connections.

These corner posts are tubular with slots 11 at 40 the top, which slots are closed by fixed caps 12, preferably octagonal, having cushions for contact with a casket to be carried thereon. The said slots are located in the inner face of each post midway between a side and adjacent end frame, and preferably only one slot to each post.

Inside each of these posts and opposite the slot is mounted a slidable member 13, preferably a hollow block, having near its lower end a lateral projection 14 extending through the slot and then widened out for pivotal connection to adjacent upper ends of the bars of side and end frames. This widened portion is preferably formed by diverging wings 15 extending upward, provided on their tips with bosses 16 having

tapped holes for stud bolts, or otherwise adapted for pivotal connection to the bar frames.

A thumb screw 17 is transversely mounted in the slidable member between said wings, and on its inner end is mounted a curved chafing plate 18 in a recess of said member, adapted to bear against the inside of the post by turning said screw, and thus lock the member in any adjusted position. This plate avoids marring the inside surface of the post by direct engagement of the 10 screw thereon, which would obstruct sliding movement of said member.

In the bottom end of each post is mounted a bushing 19, closed at its upper end. A stem 20 of a caster wheel-carrying yoke 21, is rotatably 15 mounted in said bushing and is preferably provided with a ball 22 at the top. The stem has an annular groove 23, and pins 24 mounted in the bushing project into said groove to hold the stem rotatably in the bushing.

20 A wide annular flange 25 on the stem below the post, has vertical holes therein which are engaged by a slidable trip, pin 26 mounted in a collar 27 on the end of the post, to lock the stem from turning when desired. A double pointed 25 spring 28 in said collar enters a recess in the pin to hold the pin in raised and lowered positions. The pin is readily adjusted by hand or foot by means of a bent upper end 29.

This collar has a triangular lateral lug with 30 tapped bearing faces 30 for pivotal connection with the lower ends of adjacent bars in the side and end frames 9 and 10. Intermediate bearing faces 31 in the four collars are similarly adapted for pivotal connection with the outer ends of bars 35 32 diagonally disposed within the truck frame. The inner ends of said bars are rounded on their lower corners and square on their upper corners (Fig. 2A), and pivotally connected to respective sockets in a center handle block 33, so as to limit 40 the downward movement of said block by engaging said upper corners with the respective sockets when pushed below the horizontal plane through said bars (Figs. 1 and 2). The handle block thus locks the diagonal bars in their lowest 45 position and braces the corner posts in their most widely separated position (Fig. 1). Smaller sizes of trucks are formed by raising the center handle to pull inward the corner posts, and locking the slidable members 13 in their corresponding 50 positions inside the posts by the thumb screws 17.

In the closed position of the truck (Fig. 3) the center handle is raised above the corner posts by the diagonal bar connections to a position con- 55

venient for grasping and the caster wheel forks are locked by the trip pins 26.

I claim:

5 A casket truck comprising a rectangular frame of extendible bars and tubular corner posts having vertical slots in their inner faces, slideable members mounted inside said posts having lateral

projections through respective slots and provided with diverging wings pivotally engaging adjacent bars, and a thumb screw mounted in each member between said wings and extending through said member to exert pressure on the inside of 5 the post, substantially as described.

HARRY T. FLOYD.
